UNITED STATES PATENT OFFICE

DEE L. SHEAFOR, OF CHICAGO, ILLINOIS, ASSIGNOR TO THE BLACK-CLAWSON COMPANY, OF HAMILTON, OHIO, A CORPORATION OF OHIO

PAPER-MAKING MACHINERY

Application filed September 14, 1925. Serial No. 56,258.

The present invention relates to paper making machinery, and particularly the press part of the paper making machinery which includes a traveling felt upon which the newly-formed sheet of paper is received for treatment.

One of the principal objects of the invention is to provide means for treating or washing the traveling felt of such a machine whereby to increase the life thereof as well as to improve the quality of the paper treated thereon.

Other objects of the invention will be apparent from the following description when taken in connection with the accompanying drawings in which:

Fig. 1 is a side elevation of a paper making machine embodying the present invention, parts thereof being illustrated somewhat diagrammatically to more clearly illustrate the invention;

Fig. 2 is a plan view of Fig. 1, certain parts being broken away or omitted for clearness in illustration; and

Fig. 3 is a section on the line 3—3 of Fig. 2.

Referring to the drawings, 20 denotes the traveling felt of the paper making machine which felt is formed as a continuous belt and travels in the direction indicated by the arrow in Fig. 1. The traveling felt may be guided in its movement by a series of guide rolls, two of which are illustrated at 21 and 22, these guide rolls being journaled upon the stands 26 and 27 forming part of the frame work of the paper making machine.

It will be understood that in the normal operation of the machine the newly formed paper is transferred to the surface of the traveling felt which latter carries the paper through a series of pressure rolls which are arranged in pairs, the purpose of this operation being to compact the paper or to compact and dry the same. The upper and lower rolls of a pair of pressure rolls are indicated at 23 and 24, respectively, in Fig. 1, and it will be understood that the pair of pressure rolls illustrated are the last of a series of pairs through which the paper passes before it is removed from the traveling felt 20.

Secured to the stands 26 and 27 by means

of brackets 30 and 31 are a pair of supporting or guide rods 32 and 33 which extend in a generally horizontal direction across the end of the frame work carrying the traveling felt. Slidably mounted upon the guide rods 32 and 33 is an elongated suction box 34 having its long axis disposed transverse to the direction of travel of the felt and having one face thereof so disposed with reference to the traveling felt 20 that the latter passes over the surface of the suction box in traveling from the guide roll 21 to the guide roll 22. The suction face of the suction box which is adapted to lie against the surface of the felt is provided with suction openings or slots 35 which may be a large number of small openings distributed over the suction face as illustrated in Fig. 2, or which may be larger openings still fewer in number, or which may be one or more narrow slots disposed upon the suction face in any desired manner, the purpose of the suction openings being to withdraw from the felt by suction the cleaning fluid which is applied to the felt in the manner which will be hereinafter described. The suction box is connected by means of the suction pipe 37 with a vacuum pump or suction producing means of any desired or usual construction.

Mounted upon the suction box is what may be termed a shower, which consists of a shower pipe 40 disposed approximately parallel with the surface of the traveling felt, and having therein a series of apertures 41 through which water or any other suitable cleaning fluid may be discharged upon the traveling felt just before the latter passes over the suction box 34. The pipe 40 is connected through flexible conduit 42 with a source of water or cleaning fluid supply, and as shown is arranged to discharge water against that surface of the felt which subsequently passes over the suction box.

The discharge of the cleaning fluid upon the traveling felt by the shower 40 and the subsequent suction action of the suction box 34 as the felt passes over its suction face serves to wash and recondition the felt, but as the suction box covers but a fraction of the width of the traveling felt, the washing and

reconditioning function thereof is limited to that fraction of the width of the traveling felt which passes over the suction box. In order to wash or recondition the entire width 5 of the traveling felt with a comparatively small box the latter is preferably given a reciprocating movement upon the guide rods 32 and 33, that is, it is moved from one edge of the traveling felt to the other, and then re- 10 turned to its original position, this reciprocating motion or travel of the suction box being preferably continuous so long as the felt is in motion.

The means for reciprocating the suction 15 box 34 includes a screw threaded shaft 45 journaled for rotation in the brackets 30 and 31, this shaft being extended beyond the bracket 30 and having its extended end journaled at 46 upon an outboard standard 48. 20 The screw threaded shaft 45 cooperates with an apertured and screw threaded block 49 carried by the suction box 34, the arrangement being such that when the shaft 45 is rotated in one direction the suction box is caused 25 to move from left to right, as viewed in Fig. 2, across the surface of the traveling felt, and when rotated in the opposite direction, the suction box is caused to move from right to ft. The endwise thrust upon the shaft 45 30 may be taken up by thrust bearing 50.

Mounted upon the shaft 45 between the stand 26 and the outboard standard 48 is a series of pulleys 52, 53, and 54, the pulley 52 being fixed or non-rotatably keyed upon the 35 shaft 45, and the pulleys 53 and 54 disposed on either side thereof being loosely mounted upon the shaft 45, so as to freely rotate thereon independently of the shaft. The loose pulleys 53 and 54 normally carry upon their 40 surfaces the oppositely moving driving members or belts 55 and 56 which belts pass over the driving pulley 57 formed on the driving shaft of the pressure roll 24, although it will be understood that the belts 55 and 56 may be 45 driven from any other suitable source of power. The belt 55 is crossed so that it causes rotation of the loose pulley 53 in one direction, as indicated by the arrow in Fig. 2, whereas the driving belt 56 causes rotation 50 of the loose pulley 54 in an opposite direction, as also indicated by an arrow in Fig. 2.

The reversal of movement of the screw threaded shaft 45 is accomplished by shifting either of the belts 55 and 56 on to the fixed pulley 52, and such shifting may be accomplished by the shifting means which will now be described. A shifting lever 60 pivoted upon bracket 30 at 61 is connected at one end with rod 62, having the loops 63 and 64 surrounding the belts, and at its other end with shift rod 65 having adjustable shifting collars 66 and 67 secured thereon. These adjustable collars 66 and 67 lie in the path of the stop lugs 68 and 69 carried by the suction box 34 and movable therewith. In Fig. 2 the

driving belt 56 is shown as connected with the fixed pulley 52 and the suction box is being moved to the left. When the suction box is opposite the left hand edge of the traveling felt the lug 68 engages the collar 66 and moves the shift rod 65 to the left, thereby shifting belt 56 to the loose pulley 54 and shifting belt 55 to the fixed pulley 52. The screw threaded shaft 45 now rotates in an opposite direction and the suction box is caused to move towards the right until the lug 69 strikes the collar 67, when the shifting means is again actuated to reverse the movement of the suction box. To prevent any accidental shifting of the belts 55 and 56 and to render more positive shifting action, the lever 60 is provided with an arm 70 which is adapted to engage the spring-pressed slidable plunger 71 mounted upon the bracket 30. The arrangement is such that during the initial movement of the shift lever 60, the arm 70 rides up on the inclined surface of the spring-pressed plunger 71 to depress the latter, but as soon as the arm 70 moves past the center of the spring-pressed plunger 71, it rides upon the oppositely inclined surface of the spring-pressed plunger, and the final part of the shifting movement is assisted and accelerated by the action of the spring-pressed plunger. Obviously, the spring-pressed plunger interposes enough resistance to the movement of the shift lever 60 to prevent any accidental shifting which might result from the vibration of the press or its moving parts, and at the same time it permits the shifting of the belts by movement of the suction box or by manual means.

In the operation of the apparatus, the suction box 34 and shower means 40 are moved back and forth across the surface of the traveling felt, from one edge to the other, as already described. During this movement the cleaning fluid which is supplied through the pipe 40 is showered upon the traveling felt and as the felt moves over the suction surface of the suction box 34, the suction action of the latter draws the cleaning fluid out of the felt together with any foreign matter which the cleaning fluid may have taken up in its passage through the felt. Any suitable cleaning fluid may be used, but I prefer to use cold water although it may sometimes be desirable to use warm water or to dissolve cleaning chemicals therein for the purpose of removing oil or similar foreign matter which may not be readily removable by the use of cold water alone. The pressure of the cleaning fluid and its mode of application to the traveling felt may be varied widely, as for example, by increasing or decreasing the number of apertures 41, or varying their dimensions to control the velocity and penetration of the jets of cleaning fluid in the felt, by varying the angle of incidence of the jets against the felt, or otherwise,

as may seem desirable. The cleaning fluid may be applied to the felt in a superficial manner so as to simply recondition the surface of the felt, or it may be applied in such a manner as to penetrate a considerable distance below the surface of the felt, or practically through the thickness of the felt, as for example, by the use of high velocity jets. The vacuum or suction pressures within the suction box 34, and the shape of the suction openings may be also varied widely to secure the desired results, and these may depend somewhat upon the mode of application of the cleaning fluid as well as upon the speed of travel of the felt and of the suction box. Thus, if the cleaning fluid is applied to the felt in a superficial manner, the suction pressure or vacuum need not be as great as otherwise in order to remove the cleaning fluid from the felt in its passage over the suction box. Through the control of the mode of application and the pressures of the cleaning fluid and of the suction pressures, I am enabled to wash or recondition the felt to any extent desired. A light or superficial application of cleaning fluid may be employed to clean the surface of the felt, or the cleaning fluid may be projected into or substantially through the body of the felt and then drawn out again by the suction box whereby the entire body of the felt is washed and reconditioned.

The washing of the felt in accordance with the present invention serves to maintain the felt in a porous condition and at a uniform thickness, thereby avoiding the gradual compacting of the felt, due to the pressure of the pressure rolls, the consequent variations in pressure of the rolls upon the paper and in the quality of the paper which follows from such variations in the pressure of the rolls, and the necessity for continually readjusting the pressure of the rolls to compensate for such compacting of the felt. The high porosity of the felt enables the press to be operated at a uniformly high pressure, thus effecting a more thorough absorption of moisture from the paper. Another advantage of the present invention is that, besides improving the quality and uniformity of the paper, it increases the life of the felt and thereby eliminates to a large extent shutting down the press for the purpose of washing or changing the felt, thus avoiding the well known losses incident to the shutting down of the press.

It is to be observed that the present invention provides a felt-washing unit which may be readily applied to a press. As herein illustrated it is positioned between the guide rolls 21 and 22 at the end of the press and operates upon a portion of the felt which is moving in a generally vertical or upright direction, and being at the end of the press, the washing apparatus is readily accessible for

the purpose of inspection, readjustment, or repair.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a paper making machine, or the like, having a traveling felt, press rolls, and guide rolls; a felt conditioner comprising a suction box having a suction opening therein, means for supporting the suction box with said opening in suction relationship with the surface of said traveling felt, a spray pipe connected to said suction box for concomitant movement therewith, said pipe being positioned on the same side of said felt as said suction box and in advance of and adjacent to said suction box and on the exterior thereof, and in spaced relation to said felt to discharge a fluid spray against said felt in advance of said suction box, and means for moving said suction box and spray pipe transversely across the said traveling felt.

2. In a paper making machine, or the like, having a traveling felt, press rolls, and guide rolls; a felt conditioner comprising a suction box having a face with a plurality of perforations therein forming a suction zone, means for supporting said suction box with said perforated face in suction relationship with the surface of the traveling felt, a spray pipe carried by the forward end of said suction box on the exterior thereof, said pipe having a plurality of perforations therein positioned in spaced relation to said felt to discharge a water spray against said felt in advance of the face of said suction box and over a portion of the felt commensurate with the width of said suction zone, and means for moving said suction box and spray pipe carried thereby transversely across the said traveling felt.

3. In a paper making machine, having a traveling felt, press rolls, and guide rolls; a suction box having a suction opening therein, spaced cross-rods upon which said suction box is slidably mounted for reciprocating movement thereon, a transversely disposed shaft having screw-threaded engagement with said suction box, a spray pipe carried by said suction box on the exterior thereof and in spaced relation to said felt to discharge a water spray against said felt on the same side of said felt as the suction box and in advance of said suction box, and means responsive to the movement of said suction box and spray pipe for rotating said transverse shaft in opposite directions to give a reciprocating movement to said suction box and spray pipe.

4. The method of reconditioning an end-

less transporting felt of a paper making machine which comprises impinging a jet of water of substantial velocity upon the felt over a portion of the width thereof while freely exposing it to atmosphere, to thereby dislodge material and move threads of the felt in one direction by the force of the jet, immediately thereafter subjecting this portion of the width of the felt to suction on the same side of the felt as the jet, to thereby withdraw water and dislodge material and pull threads of the felt in the opposite direction by the suction effect, and concomitantly reciprocating both the water jet and the suction zone back and forth transversely of the movement of the felt to effect reconditioning of the desired width of the felt.

In testimony whereof I hereto affix my signature.
